UNITED STATES PATENT OFFICE

MICHAEL W. MCARDLE, OF CHICAGO, ILLINOIS

DESIGN FOR A LAWN SPRINKLER

Application filed May 27, 1932. Serial No. 43,913. Term of patent 14 years.

To all whom it may concern:

Be it known that I, MICHAEL W. MCARDLE, a citizen of the United States, residing at Chicago, in the county of Cook and State of Illinois, have invented a new, original, and ornamental Design for a Lawn Sprinkler, of which the following is a specification, reference being had to the accompanying drawing, forming part thereof.

In the drawing—

Fig. 2 is an edge elevation;

Fig. 3 is a top view thereof.

I claim:

The ornamental design for a lawn sprinkler, substantially as shown.

MICHAEL W. MCARDLE.
